UNITED STATES PATENT OFFICE.

EMILE ALIBERT, OF PARIS, FRANCE.

AUTOMATIC NAIL-FEEDING DEVICE FOR NAILING MACHINES.

Application filed December 12, 1925, Serial No. 75,091, and in France December 12, 1924.

The present invention relates to an automatic feeding device for nails or tacks.

The special features of the invention consist in the means employed for discharging the nails; for closing the orifice during the discharge; the method of regulation for the different diameters; the safety device whereby all accidents are obviated in the event of an abnormal action taking place during the forward motion of the controlling bars; the disposition of the said bars; and the method of actuating the same.

In the appended drawings:

Figure 1 is a side elevation of the device.

Figure 2 is a bottom plan view thereof.

Figure 3 is a side elevation of the nail or tack feeding device.

Fig. 4 shows the two guides forming a nail track, which are suitably spaced apart for guiding the nails, and also shows a top view of the feeding device in the inoperative position.

Fig. 5 shows the cam controlling the main bar.

Fig. 6 is a view showing the cam controlling the auxiliary bar.

The complete feeding apparatus consists of one or more feeding devices which are constructed as follows:

The main body or holder 1 is U shape and slides upon the controlling bars and is closed by the plate 2 which is attached by means of four countersunk screws. In the said main body are formed two apertures 3 and 4 adapted to receive a pin 5 which secures the main body to one or the other of the said bars. At the lower part of the main body is formed the dovetail slot 6 in which is slidable the ejector body 7, a stud 8 being employed as an abutment for the said ejector body 7 and is received in a recess 8' in the ejector body. In the body of the ejector 7 is formed a lateral groove 9 for guiding the closing abutment 10. The stud 11 is mounted at the centre of

the groove 9 and a milled nut 12 mounted on the stud 11 serves to hold the abutment 10 in position after the same has been adjusted. A retractile spring 13 is secured at one end (by the screw 14) to the ejecting device 7 and

at the other end to a stud 15 mounted on the main body 1, and said spring serving to hold the ejector body 7 upon the stud 8 in the normal position, and brings it back should it be deflected by accidental circumstances.

The apparatus further comprises a main controlling bar 16, which is made of steel and

is slidable in bearings 17 and 18. On its left hand side is mounted the forked holder 19 carrying a roller 20 which rotates upon its axle 21 which is held in place by the pin 22 and the washer 23. Upon the turned part of the device adjacent the bearing 17 are slidably mounted the rings 24 and 25 serving as abutments for the retractile spring 26. At the right hand end and in the flat part, in the interior, is disposed the stud 27 which serves to bring the auxiliary bar into the proper position. The stop-piece 28 mounted in the bar 16 and secured thereto by the countersunk screw 29 and a centering member 30, has a tapered face 28', which contacts with the supporting frame of the feeding device, not shown. In the upper face of the bar 16, suitable apertures are formed for the insertion of the stud 5.

An auxiliary steel bar 39 is employed in the said apparatus; the left hand end of said bar being disposed adjacent the bearing 17. The right hand end of the bar is provided with an extension 17' and to which is secured a tempered steel plug 31 by means of the pin 32. Upon the bearing 18 is mounted a washer 33 serving as an abutment for the spring 34 which encircles the extensions 17' and serves to control the bar 39. In the bar is formed a groove 35, and coacting therewith is a stud 27 which serves to bring the said bar into the initial position. At the upper part there are provided suitable apertures 27' engaging the studs 5.

The bearings 17 and 18 are secured to the main frame by the round headed screws 36.

A cam 37 controls the main bar 16; said cam being actuated at each revolution either by the lever actuated by the nailing head of the nailing device, or by means of bevel pinions actuated by the driving shaft.

The double cam 38 serves as an abutment by means of its projections and is actuated, for each $\frac{1}{4}$ revolution, by a lever operated by the nailing head of the nailing device, or by means of bevel pinions driven by the main power shaft. The said cam is utilized only when it is desired to alternately place a different number of nails during each revolution. In a given position, when the recesses in the said cam coincide with the plug 31, the two bars 16 and 19 are controlled by the cam 37 and the spring 34. In the other position, when the projecting part of the said cam 38 coincides with the plug 31, the bar 39 will be held in the fixed position.

The main bar 16 will be actuated by the cam 37 which abuts upon the roller 20, and the stud 37 slides in the groove in the bar 39. In this movement, only the feeding elements 5 which are mounted upon the main bar 16 will be actuated.

The main body of the ejecting device 7 is made of tempered steel. The adjustable closing stop-piece 10 is also made of tempered 10 steel; these two parts are secured together, so that there will be no dropping of the nails in any position of the apparatus.

With the use of the above-mentioned safety device, there will be not risk of gripping or of 15 breakage of the ejector point 7, or of the ejector itself, or of the other parts of the apparatus.

Since the abutment contact takes place above the heads of the nails, the latter may 20 have irregular edges without interfering with the proper operation of the apparatus. An essential feature consists in the fact that the main body of the nail comes into contact with the said closing and abutment element. 25

I claim:

1. A nail feeding mechanism for nailing machines comprising a plurality of race ways, means for feeding nails therefrom including 30 U-shaped members for cooperation with the race ways, bars supporting said U-shaped members, means for securing said U-shaped members to either of the bars, ejectors slidably connected with the U-shaped members, 35 means for limiting the sliding movement of the ejectors, closing abutments for said race ways slidably adjustable on the ejectors, and

means for holding the closing abutments in adjusted positions.

2. A nail feeding mechanism for nailing 40 machines comprising a plurality of race ways, means for feeding nails therefrom including U-shaped members for cooperation with the race ways, bars carrying said U-shaped members, means for securing said U-shaped members to either one of the bars, ejectors slidably connected with the U-shaped members, 45 abutments carried by the U-shaped members, means for normally holding the ejectors yieldably engaged with the abutments, and closing abutments for the race ways slidably 50 connected with the ejectors.

3. A nail feeding mechanism for nailing machines comprising a plurality of race ways, means for feeding nails therefrom including 55 U-shaped members for cooperation with the race ways, bars carrying said U-shaped members, cover plates for holding said members on said bars, means for securing said U-shaped members to either one of the bars, 60 a groove formed in the bottom portion of each of said U-shaped members, abutments disposed at the ends of said grooves, ejectors slideable in said grooves and spring held in engagement with said abutments, and having 65 lateral grooves, closing abutments for said race ways received in said lateral grooves, and adjustable therein, and means for retaining said closing abutments in their adjusted 70 positions.

Signed at Paris in the county of Seine and State of France this twenty-seventh day of November A. D. 1925.

EMILE ALIBERT.
